UNITED STATES PATENT OFFICE.

STEPHEN W. BAND, OF SAN FRANCISCO, CALIFORNIA, ASSIGNOR OF ONE-HALF TO
WILLIAM HACKETT, OF OAKLAND, CALIFORNIA.

LOCKING BOLT.

Application filed March 14, 1922. Serial No. 543,694.

To all whom it may concern:

Be it known that I, STEPHEN W. BAND, a citizen of the United States, and a resident of San Francisco, county of San Francisco, 5 and State of California, have invented a new and useful Locking Bolt, of which the following is a specification.

My invention relates to an improved locking bolt, especially adapted in use as a 10 means for holding or clamping plates or the like together without the use of the customary threaded bolt structure commonly employed for this purpose.

The primary object of the invention is to 15 provide means which may be conveniently used for permanently or temporarily clamping plates or the like and the existing novelty renders the same especially adapted for use where it is desirable to clamp two or 20 more plates together preparatory to riveting or otherwise fixing them together.

In the accompanying drawing which illustrates the salient features, Figure 1 is a perspective view of the block which forms a 25 part of the invention, Figure 2 is a perspective view of the wedge, Figure 3 is a view in vertical section on the line 3—3 Figure 4, Figure 4 is a vertical section on the line 4—4 Figure 3 and Figure 5 is a plan view of the 30 key which is used as a locking element.

Referring now to the drawing in detail (A) and (B) represent plates with which the device may be used as a means for clamping them together either temporarily or permanently. The plates, especially those used in shipbuilding or in other like uses, are usually provided with rivet openings at spaced intervals along the edges or in other places in the body thereof. Sometimes the overlapping edges of the plates are clamped together and then again the two or more thicknesses of plates are fixed together. At any rate, in using the device the bolt (1) is passed through two or more registering 45 openings in the plates with the head (2) thereof providing a bearing on the underside of the lowermost plate. The opposite end of the bolt is preferably constructed with a reduced portion (3) leaving a button (4)

50 at its extremity with the reduced portion (3) made to cooperate with the locking element such as the slotted key (5) the same having an opening (6) made to slip over the button (4) and a slotted opening (7) 55 made to straddle the reduced portion (3).

The key (5) is adapted to confine the washer (8) on the bolt as well as the block (9); both the washer and the block are made with openings through which the bolt is passed. (10) represents a wedge which is adapted to 60 be introduced between the top one of the plates (A) and (B) and the block (9) to effect the desired clamping of the plates. Any number of the washers (8) may be used to build up a space between the plate 65 (A) and the locking element, for instance, the key (5) so that the wedge may cooperate with the block (10) to produce the desired results.

The wedge (10) is made with an open ended slot (11) so that the same may straddle the bolt and in order that the block (9) may effectively cooperate with the wedge in producing the clamping effect the block is made with V-shaped slots (12) arranged 70 parallel to one another on the underside of the block and made to receive the angular tracks (13) on opposite sides of the slot (11) of the wedge. Arranged preferably along the outside edges of the wedge (10) are a 75 series of teeth (14) the same slanting toward the greater thickness of the wedge and made to receive the headed ends (15) of the spring fingers (16) formed along two outer edges of block (9). These spring fingers (16) 80 are cut out of the material of the wedge (9) and the spring quality of the same is used to permit the heads (15) to ride over the teeth (14) of the wedge when the wedge is wedged between the block and the plates 85 by driving the same with a hammer. The wedge is struck with the hammer at the thickest end of the same and when the device is to be released the key (5) is removed.

It will be readily appreciated that the 90 spring quality of the finger (16) will enable the wedge (10) to be held firmly in any desired wedging position relative to the block and since the heads (15) of the fingers are firmly seated in the teeth there will be no 95 likelihood of the same slipping loose regardless of the force which is imposed on the device.

I claim:

A locking bolt provided with a shank 105 having a head at one end with its opposite end made to co-operate with a locking element, said shank adapted to be passed through two or more plates to be clamped together with said plates confined thereon by 110

said locking element, a block having an opening, said shank adapted to be passed through said opening for confining the block on the shank, and a slotted wedge having teeth on opposite sides of the slot, said wedge adapted to straddle the shank of the bolt between said block and said plates, with spring fingers on said block engaging the teeth of the wedge for maintaining the wedge in clamping relation with the plates, said spring fingers being cut as integral parts of the block and

formed on opposite sides of the block and embodying in their construction headed ends made to engage the teeth of the wedge, a pair of parallel inverted V-shaped grooves 15 on the block on opposite sides of the slot therein, and a pair of inverted V-shaped tracks on the wedge made to cooperate with said V-shaped grooves on the block to guide the block on the wedge.

STEPHEN W. BAND.
